(57) **CLAIM**

The ornamental design for a combination medical clamp and medical coupler, as shown and described.

DESCRIPTION

FIG. 1 is a perspective view of the combination medical clamp and medical coupler of our new design;

FIG. 2 is a front elevational view of the design of FIG. 1;

FIG. 3 is a rear elevational view of the design of FIG. 1;

FIG. 4 is a left side elevational view of the design of FIG. 1;

FIG. 5 is a right side elevational view of the design of FIG. 1;

FIG. 6 is a top plan view of the design of FIG. 1;

FIG. 7 is a bottom plan view of the design of FIG. 1;

FIG. 8 is a perspective view of the medical clamp of the design, shown removed from the medical coupler for ease of illustration;

FIG. 9 is a front elevational view of the design of FIG. 8;

FIG. 10 is a rear elevational view of the design of FIG. 8;

FIG. 11 is a left side elevational view of the design of FIG. 8;

FIG. 12 is a right side elevational view of the design of FIG. 8;

FIG. 13 is a top plan view of the design of FIG. 8;

FIG. 14 is a bottom plan view of the design of FIG. 8;

FIG. 15 is a perspective view of the medical coupler of our new design, shown removed from the medical clamp for ease of illustration;

FIG. 16 is a top plan view of the design of FIG. 15;

FIG. 17 is a bottom plan view of the design of FIG. 15; and,

FIG. 18 is an elevational view of the design of FIG. 15.

The phantom lines of FIGS. 1-7 form no part of the claimed design.
